(57) **CLAIM**

The ornamental design for a desk, as shown and described.

DESCRIPTION

FIG. 1 is a perspective view of a desk embodying our new design;

FIG. 2 is another perspective view of the desk;

FIG. 3 is a front perspective view of the desk; and,

FIG. 4 is a top plan view of the desk.

The broken lines showing the rear of the center desk drawer are for environmental purposes only and form no part of the claimed design.

1 Claim, 4 Drawing Sheets
